J. LEDWINKA.
HINGE STRUCTURE.
APPLICATION FILED JULY 1, 1919.

1,412,881.

Patented Apr. 18, 1922.

UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

HINGE STRUCTURE.

1,412,881.

Specification of Letters Patent. Patented Apr. 18, 1922.

Application filed July 1, 1919. Serial No. 307,921.

To all whom it may concern:

Be it known that I, JOSEPH LEDWINKA, a citizen of the United States, residing at Philadelphia, in the county of Philadelphia, 5 State of Pennsylvania, have made a certain new and useful Invention in Hinge Structures, of which the following is a specification.

This invention relates to hinge structures 10 of the type called outside hinges.

The object of the invention is to provide a hinge structure which is simple, inexpensive to manufacture, and easy of application, and wherein the hinged part may be readily 15 removed or replaced.

A further object of the invention is to provide a hinge structure of the nature referred to, which is specially adapted for use in connection with automobile doors.

20 Other objects of the invention will appear more fully hereinafter.

The invention consists substantially in the construction, combination, location and relative arrangement of parts, all as will be 25 more fully hereinafter set forth, as shown in the accompanying drawing and finally pointed out in the appended claims.

In the drawing,—

Fig. 1 is a view in side elevation, parts 30 broken off, of an automobile body, showing the application thereto, or to the door thereof, of a hinge structure embodying the principles of my invention.

Fig. 2 is a view in horizontal section 35 through the hinge structure on the plane indicated by line 2, 2, Fig. 1, looking in the direction of the arrows.

Fig. 3 is a broken detail view in perspective, parts in section and parts broken out, 40 showing a hinge structure embodying the invention.

The same part is designated by the same reference numeral wherever it occurs throughout the several views.

45 Generally speaking, a hinge structure embodying my invention comprises or includes two members, one designed to be secured to a post, for example, the door post of an automobile body, and the other to the member to be hinged thereto, for example, the automobile body door, the two members of the hinge being suitably pivoted together, and the invention resides particularly in the means for detaching, securing or clamp-

ing the door post member of the hinge structure, the object being to provide a clamp structure therefor, which permits the easy insertion or withdrawal of the hinge member.

In the accompanying drawing, 4 designates one member of the hinge structure, 5 and 5 the other member thereof. The member 5 is in the form of a curved arm, having one end suitably secured to the door, window or other member to be hinged. In the particular form shown, to which, however, my 65 invention is not to be limited or restricted, the arm 5 extends into the box or casing 7, and at the edge of the window or door, and is secured therein by means of screws indicated at 8, or otherwise, as may be convenient. The projecting end of the curved arm 5 is connected by a hinge bolt 9, to the barrel or hub forming the outer end of the hinge member 4. This hinge member 4 is 70 in the form of a pin adapted to be inserted through the wall into the interior of the casing 10, constituting, for example, the door post of an automobile body. Within the casing 10 is suitably bolted, spot welded or otherwise secured, a block member 11, 75 through which pass bolts 12, the members of which indicated at 13, Fig. 2, are accessible from the exterior of the casing 10. Upon these bolts is threaded a clamp member 14, which by turning screw bolts 12 may be 80 drawn towards the block 11, to constitute a clamp device. The inner ends of the bolts 12 may be headed as shown in Fig. 2. The 85 opposing faces of the blocks 11, 14, are correspondingly grooved to form a seat into which the hinge pin member 4 may be inserted. 90

After the hinge pin member 4 is inserted between the clamp blocks 11 and 14, by turning up the screw bolts, 12, the hinge pin member 4 is securely clamped and retained 95 in position. In order to remove the hinged door, window or the like, it is only necessary to back up on the screw bolts 12 to release the clamp lock 14, thereby permitting the 100 entire hinged structure to be withdrawn from the post. It will also be seen that by the construction above described, the extent to which the pivot pin members 4 project into the post or casing 10 may be varied as may be desired.

105 If desired, and in order to conceal the openings through which the hinge members 4, 5, extend into their respective casings 7,

10, suitable shoulders 15, 16, may be formed on said members to fit snugly up against the exterior walls of their respective casings.

Of course, it will be understood that each 5 door or window structure will be supplied with as many hinges as may be required.

The hinge structure constructed as above described is not only simple and inexpensive to construct and apply, but affords a strong 10 substantial support for the hinge member and permits desirable adjustment thereof, facilitates the application of the hinge member to its supporting post structure, and ready and easy detachment of the same therefrom.

Having now set forth the objects and nature 15 of my invention, and having shown and described a structure embodying the principles thereof, what I claim as new and useful and 20 of my own invention and desire to secure by Letters Patent is:

1. A structure of the class described comprising two hinge members pivotally connected together, and a pair of clamping members, one being relatively fixed and the other 25 adjustable to and from the fixed member, one of said hinge members being disposed between and rigidly held by said clamping members.

30 2. A structure of the class described comprising the combination of a hollow chamber, a pair of hinge members pivotally connected together, one of said hinge members being inserted through one wall of said chamber, 35 and means, accessible and operable through another wall of said chamber, for clamping said hinge member within the chamber.

3. A structure of the class described comprising a pair of hinge members pivotally 40 connected together, a pair of clamping members, one being relatively fixed and the other adjustable to and from the fixed member, one of said hinge members being adjustably positioned between said clamping 45 members, and means for rigidly securing and clamping said hinge member in its adjusted position.

4. The combination with a hollow post of 45 a clamp member secured within said post, 50 a clamp block cooperating therewith, a hinge

pin adapted to extend into said post and to be received and releasably clamped between said clamp member and block, means accessible from without the post for adjusting said block to and from said clamp member, 55 and a cooperating hinge member pivotally connected to said hinge pin.

5. The combination with a hollow post of a clamp member secured within said post, a hinge pin adapted to extend into said post 60 and to be received in said clamp member, means accessible from the exterior of the post for releasably clamping said pin in said clamp member, and a cooperating hinge member pivotally connected to said hinge 65 pin.

6. The combination with a hollow post, of clamp members arranged therein, a hinge member extending into the post to be received between and clamped by said clamp 70 members, a door or other part to be hinged, and a cooperating hinge member secured to the door and pivotally connected to the first named hinge member.

7. The combination with a hollow post, of 75 clamp members arranged therein, a hinge member extending into the post to be received between and clamped by said clamp members, a door or other part to be hinged, and a cooperating hinge member secured to 80 the door and pivotally connected to the first named hinge member, and means accessible from the exterior of the post for moving said clamp members towards and from each other to clamp or release said hinge member. 85

8. A hollow post, a clamp member secured within said post, bolts extending through said clamp member, and accessible from the exterior of said post, a cooperating clamp block carried by said bolts, a hinge pin adapted to extend into said post to be received and releasably clamped by said clamp member and block, a cooperating hinge member pivotally connected to said hinge pin, and a door or other part to be hinged, to which 90 95 said cooperating hinge member is connected.

In testimony whereof I have hereunto set my hand on this 27th day of June, A. D., 1919.

JOSEPH LEDWINKA.
